A. TRAUBE,
DOOR OPERATING MECHANISM.
APPLICATION FILED JAN. 16, 1920.

1,364,595.

Patented Jan. 4, 1921.

Inventor
Abraham Traube
By His Attorney
Mr. Wallace White

UNITED STATES PATENT OFFICE.

ABRAHAM TRAUBE, OF BROOKLYN, NEW YORK.

DOOR-OPERATING MECHANISM.

1,364,595.

Specification of Letters Patent.

Patented Jan. 4, 1921.

Application filed January 16, 1920. Serial No. 351,823.

To all whom it may concern:

Be it known that I, ABRAHAM TRAUBE, a citizen of the United States of America, residing at Brooklyn, county of Kings, and 5 State of New York, have invented new and useful Improvements in Door-Operating Mechanism, of which the following is a specification.

This invention relates to improvements in 10 door operating mechanism, the object of the invention being to provide means adapted to be placed in the path of a vehicle when the same is being driven into or out of the garage or barn whereby the weight of the 15 vehicle will cause the door of the garage or barn to be automatically opened or closed.

A further object of the invention is to provide door operating mechanism of the character set forth which may readily be 20 adjusted for operation by vehicles of different weights.

With the foregoing and other objects in view, the invention consists in the novel features of construction and combination of 25 parts which will be more fully described hereinafter and particularly pointed out in the claims.

The drawing accompanying and forming 30 part of this specification is a sectional side view of one embodiment of my improved means for setting the door opening and closing mechanism in operation, the upper portion of the drawing being intended to illustrate diagrammatically the door and its 35 opening and closing mechanism.

Referring to the drawing, 2 designates a suitable casing or box which is adapted to be let into the sidewalk or the driveway to a garage, said box having a floating cover 3 adapted to lie flush with the surface of the sidewalk or driveway and to be depressed within the box under the weight of a vehicle passing thereover, the side walls of the box being provided with an inwardly extending 45 flange 4 which is adapted to limit the downward movement of the cover 3. The cover is supported flush with the top edge of the box by a plurality of helical springs 5, these springs being preferably spaced at equal distances apart around the interior of the box, it being understood of course that the box may be of any desired form in cross-section. The bottom of the box, as well as the cover 3, may be provided with a plurality of lugs 50 or rods extending inwardly a short distance for maintaining the springs against sidewise

shifting. One of the features of the present invention is that the depressibility of the cover 3 may readily be changed. For instance, it is contemplated that for ordinary use the springs supporting the cover will be capable of resisting depression by any weight less than two thousand pounds. Should it be desired, however, to render the cover 3 depressible by a vehicle of less 60 weight, it is necessary only to lift the cover out of the box and remove a sufficient number of the springs so that the cover will be depressed by the weight of the vehicle to which it is desired to adapt the apparatus. 65

For permitting the door 6 to be opened upon the depression of the cover 3, a shaft 7 is supported for rocking movement in the side walls of the box 2, the shaft having an arm 7' extending radially therefrom and 70 provided at its free end with a roller 8 adapted to be maintained in contact with the under face of the cover 3 by means of a coiled spring 9. On the shaft 7 is secured a pulley 10, to which is fastened one end of a cable 11 which may be trained over pulleys 12 and 13 and have its opposite end secured to one member 14 of a latch, the latch member being pivoted at one end and held by means of a spring 16 and normally 75 held in contact with the other member 15 of the latch, which is secured to the door 6. It will be understood, of course, that the cable 11, from the point where it emerges from the box 2 to the point where it is connected to the latch member 14 may be incased in a 80 suitable conduit, not shown, and that as many pulleys may be placed in position as are necessary to properly guide the cable around corners, etc. For causing the door 85 to slide open when the latch members are disengaged by means of the cable 11, a weight 17 is herein illustrated attached to the end of a cable 18 passing over a pulley 19 mounted on the door frame, the opposite 90 end of the cable being secured to a fastening member 20 fixed to the door. It will thus be seen that when sufficient weight passes over the cover 3 the shaft 7 will be rocked and thereby the cable 11 wound sufficiently 95 on the pulley 10 to lift the latch member 14 out of contact with its co-operating latch member 15 whereby the door will be pulled open by means of the weight 17. 100

For the purpose of permitting the door 110 to be automatically closed in response to the depression of the cover or plate 3, I

have illustrated herein a motor 21, to the shaft of which is secured a pulley having secured thereto one end of a cable 22, which cable may pass over pulleys 23 and 24 and have its opposite end secured to the fastening member 20 on the door. It will thus be seen that when the circuit through the motor is closed the cable 22 will be wound on the pulley carried by the motor shaft and thus 10 pull the door into closed position. The arrangement must be such that when the door is completely closed the motor circuit is open and when the door is completely opened the motor circuit will remain open 15 until sufficient weight is applied to the cover or plate 3 to depress the same. For this purpose I have provided a switch device comprising a plurality of pivoted members 25, 26 and 27 connected together by means 20 of a rod 28. The upper edge of the door 6 is provided with a trip portion 29 adapted to contact at the proper times with the pivoted members 25 and 27 to open and close the circuit to the motor. One of the terminals 25 of the motor is connected by conductor 30 to one pole of a battery 31, the pole of which is connected by a conductor 32 to a contact point carried by a bracket 33 secured within the box 2 and insulated therefrom. The other terminal of the motor is connected by a conductor 34 to a contact point secured on the framework of the door in the path of the pivoted member 26, while a conductor 35 is secured at one end 30 to the member 26 and at its opposite end to a contact point carried by the arm 7' in the box 2. From the construction described it will be seen that when the door is completely closed, as shown in the drawing, the switch member 26 will have passed out of contact 35 with the coöperating contact point and therefore no circuit can be established through the motor even though the plate 3 is now depressed until the arm 7' comes into contact with the bracket 33, so that, with the door in its closed position the passage of a vehicle over the plate 3 merely rocks the shaft 7 and releases the latch member 14 so that the door will be operated into open 40 position by means of the weight 17. As soon as the door has been moved rearwardly until the trip projection 29 strikes the switch member 27, the switch member 26 is swung on its pivot back into engagement with the coöperating contact point. At this time, however, the vehicle has passed off the plate 3, and therefore 45 the contact between the arm 7' and the bracket 33 is broken and thus no current 50 can pass through the motor so that the door remains in its open position. When the vehicle is driven out of the garage and onto the plate 3, however, immediately the arm 7' contacts with the bracket 33, and the switch member 26 being at this time in contact with

the coöperating contact point, the circuit through the motor is closed and the motor is thereby operated to close the door. As soon as the trip member 29 of the door strikes the switch member 25, the vehicle must be 70 driven off the plate 3, whereupon the coöperating latch members 14 and 15 operate to fasten the door.

It will be understood, of course, that in places where it is desired to have the door 75 automatically closed as soon as the vehicle is driven into the garage, a duplicate of the box 2 and its operating members may be placed within the garage. It will also be understood that mechanism may be provided in addition to that shown herein, for releasing the latch members by hand and also for closing the circuit of the motor by hand when desired. These features form no part of the present invention and therefore 85 I have deemed it unnecessary to illustrate such mechanism.

While I have described in detail the structure herein illustrated, it is to be understood that I do not thereby limit my invention to 90 the precise features of construction shown, since I am aware that many mechanical changes and modifications may be made therein without departing from the spirit and scope of the invention as set forth in 95 the claims appended hereto.

Having thus described my invention, what I claim is:

1. The combination with a door provided with a latch and means for operating the 100 door in one direction upon release of the latch, of a rock shaft, means carried by said shaft for releasing the latch when the shaft is rocked, means also carried by said shaft for causing operation of the door in 105 the opposite direction, and bodily depressible means for rocking said shaft whereby the door is operated in opposite directions on successive depressions of said means.

2. The combination with a door provided 110 with a latch and means for operating the door in one direction upon release of the latch, of a rock shaft, means carried by said shaft for releasing the latch when the shaft is rocked, means also carried by said shaft 115 for causing operation of the door in the opposite direction, bodily depressible means for rocking said shaft whereby the door is operated in opposite directions on successive depressions of said means, and means 120 for varying the depressibility of said last means.

3. The combination with a door provided 125 with a latch and means for operating the door in one direction upon release of said latch, of a rock shaft, means carried by said shaft for releasing the latch when the shaft is rocked, means also carried by said shaft for causing operation of the door in the opposite direction, a bodily depressible plate 130

for rocking said shaft whereby the door is operated in opposite directions upon successive depressions of said plate, and a plurality of removable springs for supporting

5 said plate.

4. The combination with a slideable door, of a latch for retaining the door closed, means operative to open the door upon release of said latch, electrically operated

10 means for closing the door, a circuit controlling device projecting into the path of

the door and operable thereby into circuit opening and closing positions respectively immediately prior to the arrival of the door at the limit of its closed and opened positions, and depressible means for releasing

15

said latch and for completely closing the circuit when the door is fully opened.

In testimony whereof I have signed my name to this specification.

ABRAHAM TRAUBE.
